US00D581925S

(12) **United States Design Patent**
Otsuka

(10) **Patent No.:** **US D581,925 S**
(45) **Date of Patent:** **** Dec. 2, 2008**

(54) **EMULATOR FOR A MICROCOMPUTER**

(75) Inventor: **Hitoshi Otsuka**, Yokosuka (JP)

(73) Assignee: **Kabushiki Kaisha Toshiba**, Tokyo (JP)

(**) Term: **14 Years**

(21) Appl. No.: **29/280,349**

(22) Filed: **May 24, 2007**

(30) **Foreign Application Priority Data**

Mar. 9, 2007 (JP) 2007-006218

(51) **LOC (8) Cl.** **14-02**

(52) **U.S. Cl.** **D14/356**

(57) **CLAIM**

The ornamental design for an emulator for a microcomputer, as shown and described.

DESCRIPTION

FIG. 1 is a front, top and right side perspective view of an emulator for a microcomputer, showing my new design;

FIG. 2 is a front elevational view thereof;

FIG. 3 is a top plan view thereof;

FIG. 4 is a rear elevational view thereof;

FIG. 5 is a bottom plan view thereof;

FIG. 6 is a left side elevational view thereof; and,

FIG. 7 is a right side elevational view thereof.
